UNITED STATES PATENT OFFICE.

JOHN B. WITTY, OF INDIANAPOLIS, INDIANA.

RAIL-CO尤LING.

SPECIFICATION forming part of Letters Patent No. 317,065, dated May 5, 1885.

Application filed March 25, 1884. (No model.)

To all whom it may concern:

Be it known that I, JOHN B. WITTY, of the city of Indianapolis, county of Marion, and State of Indiana, have invented certain new and useful Improvements in Rail-Couplings, 5 of which the following is a specification.

My said invention consists in an improved construction of rail-couplings for use in railway-switches, by the use of which the rails 10 may be easily and tightly clamped and rigidly held in position, as will be presently more particularly set forth.

Referring to the accompanying drawings, which are made a part hereof, and on which 15 similar letters of reference indicate similar parts, Figure 1 is a transverse section of a railway-track alongside a coupling embodying my said invention and a switch-stand connected thereto; Fig. 2, a top or plan view of 20 the same as seen when looking downwardly from the dotted line $y y$; Fig. 3, a transverse section on an enlarged scale on the dotted line $z z$ of the portion which embodies my present invention; and Fig. 4, a view similar to Fig. 3, 25 showing my invention as applied to double-throw switches.

In said drawings, the portions marked A represent the head-blocks, on which the switch 30 is mounted; B, the switch-stand; C, a tie-rod, which forms a part of the coupling, and D a 35 brace-rod placed between the rails, which forms the other part of the coupling.

The head-block A, switch-stand B, its operating-rod B', the connecting-rod B², and the 40 railroad-rails are shown to illustrate the application and operation of my improved rail-coupling, and do not constitute any part of my present invention. They will not, therefore, be further described herein, except incidentally in the description of said rail-coupling, which alone forms the subject-matter of 45 this application.

The tie-rod C is coupled to the connecting-rod B² in the ordinary or any approved manner. It has a lip or flange, c', a short distance 50 from this connection, which is formed to fit snugly against the outer side of the rail. Its other end extends under the rails to the other side of the track, and is screw-threaded. It is provided on this end with a washer, c², the

face of which is adapted to fit snugly to the outside of the rail on this side of the track, and a nut, c³, by means of which said washer is held in place against said rail. Between the rails it is provided with upwardly-projecting 55 lugs c⁴, which extend up alongside the brace-rod D and hold it in place.

The brace-rod D is placed between the rails, and is of the required length to make the track the proper width. Its ends d are formed 60 to fit against the sides of the rails, between which it is placed. It is placed between the lugs c⁴ on the tie-bar, and it is thus prevented from getting out of place. In Fig. 4 is shown a means for coupling more than two rails, 65 which consists in simply extending the rod C to the proper length, and inserting an additional bar D for each additional rail.

The operation of my invention is as follows: The several parts being in the position shown, 70 the nut c³ is screwed up tightly against the washer c², which crowds against the outside of the rail. The lip or flange c' on the other end of the rod C at the same time draws the other rail inward, and thus the rails are drawn 75 toward each other against the ends of the brace-rod D and tightly clamped in position. If from long use or other cause the rails become loose, a partial turn of the nut is sufficient to make them perfectly tight again. When it is 80 desired to remove a rail, it can be readily done by simply backing the nut off until said rail is free from the clamps.

Having thus fully described my said invention, what I claim as new, and desire to secure 85 by Letters Patent, is—

1. In a rail-coupling, the combination of a tie-rod having a lip or projection adapted to engage with the outside of one rail, and a nut and washer on its opposite end adapted to engage with the outside of the other rail, and a brace-rod interposed between the rails, its ends bearing against the inside surfaces thereof, 90 said brace-rod being held in position by lugs connecting it with the tie-rod, substantially as described, and for the purposes specified.

2. The combination, with the railroad-rails, 95 of a coupling composed of a tie-bar adapted to be adjustably secured to the outsides of the two rails and a brace-rod interposed between 100

said rails, said brace-rod and said tie-bar being connected by lugs, substantially as set forth.

3. The combination, in a rail-coupling, of the tie-rod C, provided on one end with the lip c', adapted to fit against the outside of the rail on its end, the other end being screw-threaded and provided with a washer, c², adapted to fit against the outside of the rail on said end, and a nut, c³, adapted to operate said washer, and the brace-rod D, interposed between said rails, said tie-rod and said brace-

rod being connected by the lugs c⁴, which project from one rod and engage with the other, substantially as described, and for the purposes specified.

In witness whereof I have hereunto set my hand and seal, at Indianapolis, Indiana, this 22d day of March, A. D. 1884.

JOHN B. WITTY. [L. s.]
